[57] CLAIM

The ornamental design for a combined spray bottle and paper towel holder, as shown.

DESCRIPTION

FIG. 1 is a front view of the combined spray bottle and paper towel holder of the present invention;

FIG. 2 is a top view of the combined spray bottle and paper towel holder;

FIG. 3 is a bottom view of the combined spray bottle and paper towel holder;

FIG. 4 is a left side view of the combined spray bottle and paper towel holder;

FIG. 5 is a rear view of the combined spray bottle and paper towel holder;

FIG. 6 is a right side view of the combined spray bottle and paper towel holder; and,

FIG. 7 is a perspective view of the combined spray bottle and paper towel holder.

The broken-line disclosure of a spray head in FIG. 7 is for illustrative purposes only and forms no part of the claimed design.
